Primary Examiner — Lucy Lieberman(74) *Attorney, Agent, or Firm* — Sughrue Mion, PLLC(57) **CLAIM**

The ornamental design for a watch band, as shown and described.

DESCRIPTION

FIG. 1 is a front view of a watch band shown in an unassembled condition; and,

FIG. 2 is a front perspective view thereof.

The broken lines in the drawings are used to show portions of the watch band that do not form part of the claimed design.
